UNITED STATES PATENT OFFICE.

HARMON J. KLINE, OF LANSING, MICHIGAN.

INTERNAL-COMBUSTION ENGINE.

Application filed May 27, 1918. Serial No. 236,798.

To all whom it may concern:

Be it known that I, HARMON J. KLINE, a citizen of the United States, residing at Lansing, in the county of Ingham and State of Michigan, have invented new and useful Improvements in Internal-Combustion Engines, of which the following is a specification.

The present invention relates to improvements in internal combustion engines, and the primary object is to provide an improved engine of this class adapted to use efficiently kerosene or other relatively heavy or difficultly volatile fuel oil. To accomplish this purpose and to otherwise improve the construction and operating efficiency of internal combustion engines, the present invention provides a vaporizer wherein the fuel is vaporized and mixed with appropriate volumes of air to form the explosive charges for the cylinders under such temperature and pressure conditions as to produce and maintain a superheated substantially dry gaseous mixture prior to the entrance of the same into the cylinders, as a result of the complete vaporization of both the lighter and the heavier fractions of the fuel. Preignition of the superheated dry gaseous mixture under compression in the cylinders is prevented by internal cooling of the engine by the incoming fresh air going to make up the mixture and also by the meeting of the superheated mixture and the relatively cool incoming fresh air, and accumulation of a heavy residue within the vaporizer, due to any cracking tendency of the fuel oil therein, is prevented by a to-and-fro washing action of the fresh fuel upon such residue, which action is maintained during the operation of the engine.

The present invention also provides a vaporizer wherein such superheated dry gaseous mixture is produced by the aid of heat of combustion of the engine, it being preferable to employ for this purpose the exhaust gases, and a thermostatic control is provided whereby the amount of heat supplied to the vaporizer and hence the temperature maintained in the vaporizer is regulated automatically to compensate for variations in the speed of or load on the engine or other causes.

The invention further provides improved means for supplying and controlling the supply of fuel oil to the vaporizer, and means for supplying high-test gasoline or

other easily volatile fuel to the engine for starting, and, where desirable or necessary, for supplying water to the engine to be converted into steam before entering the cylinders, thus cooling the engine internally to prevent pre-ignition and otherwise improving the operating efficiency of the engine.

To these and other ends, the invention consists in the combination and arrangement of the several parts, all as will be herein-after more fully described, the novel features being pointed out particularly in the claims at the end of the specification.

In the accompanying drawings:

Figure 1 represents a central vertical section taken longitudinally through an internal combustion engine constructed in accordance with one embodiment of the invention.

Figure 2 represents a transverse vertical section taken centrally through one of the cylinders of the engine as shown in Figure 1.

Figure 3 is a detail sectional view, on an enlarged scale, taken centrally through the vaporizer as shown in Figures 1 and 2 and illustrating one of the priming or water supply devices in section.

Figure 4 represents a transverse section, on an enlarged scale, taken through the middle of the vaporizer, and also showing in section the exhaust pipes through which the exhaust gases are conducted to and from the heating jacket of the vaporizer.

Figure 5 is a vertical section taken centrally through the upper and lower exhaust pipes shown in Figure 4 illustrating the thermostat and the valves controlled thereby for regulating the amount of heat supplied to the vaporizer.

Figure 6 is a view of the left-hand end of the upper exhaust pipe shown in Figure 5.

Figure 7 is a view of the left-hand end of the lower exhaust pipe shown in Figure 5.

Figure 8 is a view similar to Figure 3 showing another form of atomizer or spray nozzle which may be used.

Figure 9 is a view similar to Figure 8 showing another mode of introducing the heating gases to the vaporizer.

Figure 10 is a detail perspective view of the lower end of the atomizer or spray nozzle showing a modified construction thereof.

Figures 11, 12 and 13 are detail elevations of bottom plates or disks of different forms

which may be used in connection with the atomizer or spray nozzle shown in Figure 10.

Figure 14 represents a central transverse section through a vaporizer similar to that shown in Figures 3, 8 and 9, illustrating another embodiment of the atomizer or spray nozzle.

Figure 15 is a diagrammatic view showing one of the cylinders and the respective 10 piston barrel in section and indicating the relation of the fresh mixture therein to the fresh air and the burned gases at the time the fresh mixture enters the cylinder, and

Figure 16 is a diagrammatic view showing 15 a system for supplying the fuel oil under pressure to an atomizer or spray nozzle of the type shown in Figures 8 and 9.

Similar parts are designated by the same 20 reference characters in the several views.

The primary object of the invention is to provide an internal combustion engine which is capable of operating efficiently upon kerosene or other relatively heavy or 25 difficultly volatile fuel oil, the various features of the engine having been devised with this particular object in view. The embodiments of the invention herein shown and described are preferred, but it is to be understood that the invention is not restricted to these particular constructions shown and described as equivalent constructions are contemplated and will be included within the 30 scope of the claims.

According to the present invention, the 35 engine may comprise a single pair of co-operating cylinders or any desired number of pairs of such cylinders, and where a multiple number of pairs of cylinders is employed, the cylinders may be arranged in tandem, they may be arranged in V-form as shown and described in my co-pending application, Serial No. 89599, filed April 7, 1916, or the cylinders may be arranged in any other 40 desired relation. In the present instance, the engine is shown as embodying a single pair of cylinders arranged in tandem; that is to say, both cylinders of the pair are located at the same side of the shaft with their axes 45 parallel. The engine, as shown, comprises a base 1 which forms a pair of separate or non-communicating crank cases or compartments 2, the base also providing end bearings 3 and an intermediate bearing 4 to receive the end and intermediate journals of a crank shaft 5. The crank shaft is provided with cranks 6, the crank pins of which are set in diametrically opposite positions or at an angle of 180°, and, preferably, these 50 cranks and the reciprocating elements connected thereto are counterbalanced by the counterweights 7 connected to the respective cranks. A fly-wheel 8 is fixed to one end of the crank shaft, as usual, and in 55 those cases where a starter is used with the

engine, a gear face 9 is formed on or attached to the fly-wheel to cooperate with the gearing 10 of the starter, the starting gearing shown being known as a Bendix drive. An oil pan 11 is fitted to the bottom of the 70 base and provides oil wells from which the oil is splashed by the connecting rod to lubricate the crank pin, cylinder and wrist pin. As shown, a spiral gear 12 is formed on or fixed to the shaft within one of the end 75 bearings 3, this gear cooperating with a similar gear 13 adapted to drive an oil pump (not shown), the oil pump serving to feed oil under pressure to the main crank shaft bearings, and oil is returned from the outer 80 ends of the crank shaft bearings 3 to the respective crank cases by downwardly and inwardly inclined conduits or ducts 14, ball check-valves 15 being shown for preventing backflow of oil through these conduits 85 to the bearings due to pressure within the crank cases.

The cylinder units 16, as shown, are substantially of duplicate construction. Each cylinder which is bolted or otherwise fixed 90 at its lower end to a flange 17 on the top of the engine base is provided with suitable means for cooling it. In some instances water-cooling may be desirable or necessary but it is preferable to employ air-cooling, 95 each cylinder, as shown, being provided with a number of fins 18 which are properly placed and are sufficient in number to afford the requisite cooling surface. A fan 19 may be used to induce an air current for cooling 100 the fins and cylinders, the fan being conveniently driven, as usual, from a belt pulley 20 fixed on the crank shaft. The head 21 of each cylinder has an opening extending centrally and axially therethrough and the side 105 wall of each cylinder is provided with two sets of circumferentially spaced ports 22 and 23, the upper set of ports 22 serving as exhaust ports and communicating with an annular chamber or exhaust conduit 24, 110 and the lower set of ports 23 serving to control the intake of fresh air into the respective crank case and these ports communicating with a surrounding or annular conduit 25. A piston 26 is fitted to reciprocate 115 in each cylinder, the wrist pin 27 of the piston being connected by a connecting rod 28 to the respective crank pin on the crank shaft, and the length of the piston is so proportioned with respect to the exhaust and 120 intake ports 22 and 23 that the upper end of the piston will uncover and cover the exhaust ports 22 at the proper times while the lower end of the piston will uncover and cover the air intake ports 23 at the proper 125 times. In order to prevent excess lubricating oil from reaching the cylinders, baffles 29 may be fitted at the lower ends of the cylinders as shown in Figures 1 and 2. A tubular barrel 30, which is preferably cir- 130

cular in cross-section, is fixed to the upper end of each piston, and this barrel is adapted to reciprocate through the opening in the head of the cylinder, a suitable packing 5 being provided in the cylinder head to prevent leakage from the combustion chamber 32 of the cylinder. The piston barrel is preferably constructed of seamless drawn thin steel, its lower end being preferably 10 enlarged, at 33, and provided at its lower edge with an outturned peripheral flange 34, and the barrel is preferably fixed to the piston by a ring 35 which is threaded on or otherwise fixed to the piston. The head 15 of the piston is formed with an opening 36 which extends therethrough, a valve-seat surrounding the opening, and a poppet valve 37 is arranged to cooperate with the seat and thus control the opening 36. Preferably, 20 and as shown, the stem 38 of the valve is guided by a bearing 39 forming part of a web or spider 40, this web or spider being formed integrally with or otherwise fixed in the piston below its head. The barrel 30 25 is provided near its upper end with a suitable number of circumferentially spaced ports 41 which are arranged to communicate with the combustion chamber 32 of the respective cylinder when the corresponding 30 piston approaches the limit of its downward or power stroke, as shown at the left-hand side of Figure 1, and the upper end of the barrel is open. The annular exhaust conduits 24 of the cylinders are connected to 35 a common exhaust pipe or manifold 42 and the annular air intake conduits 25 of the cylinders are connected to an intake manifold 43, the latter being preferably provided with an air strainer or an air washer, 40 an air strainer 44 being shown conventionally, and in certain embodiments of the invention a throttle valve 45 may be provided for the air intake manifold 43 whereby the 45 volume of air entering the crank case may be varied to control the speed and power of the engine in a manner that will be hereinafter described. Furthermore, in some instances it may be desirable to fit a carburetor to the intake manifold 43 to supply a gaso- 50 line and air mixture to the crank case for starting purposes.

The vaporizer is fixed to the heads of the cylinders, this vaporizer, according to the present invention, comprising an inner wall or casing 46 and an outer wall or casing 47, the space between the inner and outer walls forming a heating jacket 48. The inner wall or casing has formed within it 55 chambers 49 which are in alinement with the respective cylinders, and these chambers are adapted to receive the upper ends of the respective piston barrels as the latter move 60 upwardly with their pistons. The chambers 49 are interconnected by a venturi 50 65 the apex of which is depressed or positioned at a lower level than its ends to form a well to receive any excess, surplus or heavy fractions of fuel oil and thus prevent the direct flow of unvaporized fuel oil to the combustion chambers. Also, it is preferable 70 to form upstanding lips 51 at the junctions between the ends of the venturi and the chambers 49, these upstanding or raised lips serving to retain within the venturi the fuel oil which is subject to a to-and-fro 75 motion therein. In the embodiment of the invention shown in Figures 1-5 inclusive, the fuel oil is supplied from any suitable source through a pipe 52 to a float chamber 53, the fuel oil being maintained at a substantially constant level in this chamber by a float 54 which is connected by a lever 55 to a float valve 56, and the fuel oil flows from the float chamber through a nozzle 57 which is fitted in the bottom of the venturi 80 under control of a needle valve 58 the stem of which extends through an enlarged opening 59 in the upper wall of the venturi and is connected preferably by a ball or universal joint 60 to a piston 61, the piston being fitted to reciprocate in a cylinder 62 which is fixed in the upper wall of the float chamber as shown in Figure 4. A spring 63 is contained within the cylinder 62 and it bears on the upper side of 85 the piston 61 with a tendency to move the needle valve downwardly and hence to close the nozzle. Suitable means is preferably provided for adjusting the strength of the spring 63, the cylinder 62 in the present instance being threaded into the top wall of the float chamber 53, and a lock nut 64 is provided for holding the cylinder at the different set adjustments.

The exhaust gases which are utilized to 105 supply the heat necessary to vaporize the fuel oil within the vaporizer are conducted from the exhaust manifold 42 through a connecting pipe 65 to an inlet 66 which inlet communicates with the heating jacket 48 110 of the vaporizer at its center, and the exhaust gases are conducted from the heating jacket 48 of the vaporizer through outlets 67 which outlets are located toward opposite ends of the vaporizer and preferably 115 at points spaced equidistantly from the exhaust gas inlet 66. By so disposing the exhaust gas inlets and outlets, the gases when at their highest temperature act upon the vaporizer in the region of its apex and hence in the zone where the highest degree 120 of vaporization is required, and the equidistant spacing of the outlets 67 with respect to the exhaust gas inlet equalizes the flow of the exhaust gases through the 125 jacket 48 and hence causes equal heating of both ends of the vaporizer.

The thermostatic control provided by the present invention for automatically regulating the temperature within the vaporizer 130

comprises, preferably, a thermostat 68 and a pair of reversely acting valves 69 and 70 operatively connected thereto. The thermostat may be of different types, but it is preferable to employ one of the corrugated cylindrical bellows type containing within it a fluid of appropriate volatility. It is also preferable to so place the thermostat that it will be subject to the influence of the exhaust gases after such gases have passed through the heating jacket of the vaporizer, such an arrangement not only protecting the thermostat from excessive heat but also enabling the thermostat to accurately govern the volume of the exhaust gases entering the heating jacket of the vaporizer in accordance with the temperature existing in such jacket. As shown, the thermostat is located within an exhaust manifold 71 which communicates with and receives the exhaust gases from the outlets 67 of the heating jacket of the vaporizer. One side of the thermostat chamber bears against a stop 72 and the opposite wall of the thermostat bears upon a plunger 73, the latter operating through a wall of the manifold 71 and being connected by a rod or link 74 to a crank 75, said crank being fixed on the shaft 76 of the valve 70 which valve is contained within and serves to control the escape of the exhaust gases from the exhaust manifold 42 through its outlet 77. The valve 69 which is fitted in the outlet of the upper exhaust manifold 71 has a crank 78 fixed on its shaft 79, this crank 78 on the valve 69 being located in reverse relation to the crank 75 on the valve 70. The cranks 75 and 78 are operatively connected by a link 80. In the construction and arrangement described, the connecting link 80 between the valves 69 and 70 will cause one valve to move toward a closed position while the other valve is moving toward an open position, and vice versa. As shown in Figure 5, the valve 70 is in substantially closed position, the valve 69 being in a correspondingly open position. When the valves are in such relative positions, the major portion of the exhaust gases from the manifold 42 will be diverted through the pipe 65 and into the heating jacket of the vaporizer, these exhaust gases leaving the heating jacket of the vaporizer through the outlets 67 being free to escape through the outlet of the manifold 71. As the temperature of the vaporizer rises, the temperature of the exhaust gases leaving the heating jacket of the vaporizer rises, and these gases act upon the thermostat to expand it, in consequence of which the plunger 73 is forced downwardly, thus swinging the valve 70 toward an open position and correspondingly swinging the valve 69 toward a closed position as indicated by the arrows in Figure 5, whereby part of the exhaust gases escape directly through the outlet 77 of the manifold 42, thus reducing the volume of exhaust gases entering the heating jacket of the vaporizer through the pipe 65, and, also, the back pressure on the exhaust gases within the heating jacket of the vaporizer is reduced by the larger opening provided for the escape of these gases by the opening movement of the valve 70. After the engine has been in operation for a period sufficient to heat it to a normal running temperature, the thermostat will act to automatically maintain a substantially constant and efficient temperature within the vaporizer by expanding and contracting in accordance with an increase or a decrease in the temperature of the exhaust gases leaving the heating jacket of the vaporizer and correspondingly adjusting the heat control valves 69 and 70. Preferably means is provided for adjusting the thermostat mechanism whereby the same may be set to maintain substantially the desired temperature within the vaporizer. As shown, the stop 72 which cooperates with one wall of the chamber of the thermostat is formed as a screw which is threaded and hence adjustable axially in the top wall 81 of the manifold 71, a lock nut 82 cooperating with the screw to retain it in set adjustment. Also, it is preferable to provide a spring 83 which acts with a tendency to close the valve 70 and open the valve 69, the spring 83 shown in the present instance being connected to a crank 84 which is fixed on the shaft 76 of the valve 70, the action of the spring being transmitted also to the valve 69 through the connecting link 80. It will be understood that a suitable manual control may be connected to the valve 69 and 70 whereby these valves when desired or necessary may be set manually independently of the thermostat.

Means is provided for priming the engine whereby it may be started easily, using high-test gasoline or other easily volatile liquid as a fuel, which means may also serve to introduce water into the engine in some instances where it is desirable to assist in the interior cooling of the engine, the water being so introduced that it is converted into steam before it enters the combustion chamber of the cylinder. Preferably, and as shown, the priming and water-injecting means for each cylinder is fitted into the top of the vaporizer in substantial alignment with the chamber 49 therein and the piston barrel operative in such chamber. The priming and water-injecting means as shown comprises a reservoir 85 adapted to contain a suitable supply of gasoline or water, the peripheral wall of the reservoir being composed, if desired, of glass to make visible the contents within the reservoir, and the top 86 of the reservoir is provided

with a screw plug 87 which normally closes it but provides means for filling the reservoir. When water injection is desired, the screw plug 87 may be removed and a suitable water pump may be attached to the threaded opening into which the plug fits. The central column 88 is provided with ports 89 and 90 through which the contents in the reservoir may enter the interior bore 91 of the column and the liquid within the bore 91 may be subject to the same pressure as that acting on the liquid in the reservoir. A feed opening 92 is formed at the lower end of the bore 91 and a needle valve 93 is threaded at 94 in the upper end of the bore of the standard and its lower end cooperates with the edge of the feed opening 92 as a valve seat, the needle valve serving to regulate the amount of gasoline or water fed to the engine. A nipple 95 is fixed in the bottom of the reservoir and has a passage therethrough for the gasoline or water on its way to the engine. Preferably, and as shown, the nipple contains a glass or transparent tube 96 through which the gasoline or water fed from the opening 92 may be observed, thus enabling the operator to regulate the amount of gasoline or water supplied by adjustment of the needle valve. A plug valve 97 is fitted into the lower portion of the nipple and serves to control communication between the reservoir and the engine cylinder. The nipple which is threaded into the vaporizer casing has a tube-like extension 98 projecting therefrom, the lower end of the extension 98 terminating at substantially the level of the upper end of the corresponding piston barrel when the respective piston is at the limit of its down stroke. A tube or conduit 99 leads from a passage 100 to the top of the liquid chamber in the reservoir, the passage 100 being in communication with the sight feed tube 96, this tube 99 permitting the pressure on top of the liquid in the reservoir to be equalized with the pressure in the sight feed tube 96.

In starting the engine with gasoline, the needle valve 93 is set for the proper opening and gasoline from the reservoir then flows through the feed opening 92 into the sight feed tube 96. By opening the valve 97, such gasoline flows downwardly through the tubular extension 98 and drops upon the valve 37. During the down stroke of the corresponding piston, air compressed in the respective crank case flows upwardly past the valve 37 and causes the gasoline on the valve 37 to be mixed therewith, and when the respective piston reaches the lower limit of its down stroke, the ports 41 in the respective piston barrel will be brought into communication with the corresponding combustion chamber 32 of the cylinder and the following up stroke of the piston will then compress such mixture in the combustion chamber, the compressed mixture being ignited at the proper moment by the usual spark plug. After the engine 70 has run sufficiently long on gasoline to become heated, its operation is continued, using fuel oil, and during such operation of the engine the valve 97 is closed. However, in such cases where it is desirable to inject 75 water into the engine to be converted therein into steam, thus assisting in the internal cooling of the engine, the valve 97 is set in open position and water is supplied to the reservoir by a pump or other suitable 80 device. The water entering through the tube 98 becomes heated to the point where it is vaporized or converted into steam, this tube 98 being of such a length that water in liquid form cannot reach the combustion 85 chamber of the cylinder and thus internal rusting of the engine is avoided.

Instead of employing a piston, such as the piston 61, for controlling the fuel regulating needle valve 58, a diaphragm may be 90 used such as that shown in Figure 14. In this latter instance, a corrugated diaphragm 101 is shown, the periphery of the diaphragm being clamped around the edge of an opening in the top of the float chamber 102 by a 95 clamping ring 103 which preferably has a thread engagement with the top of the float chamber. The needle valve 104 which cooperates with the nozzle has a threaded upper portion 105 which engages in a threaded 100 sleeve 106 which is fixed in the diaphragm, and the upper end of the needle valve stem has a milled head 107 by which it may be rotated, thus adjusting the needle valve relatively to its seat in the nozzles. A milled 105 lock nut 108 serves to retain the needle valve in its different set adjustments. The atomizer in Figure 14 is shown applied to a portion of an engine in which the cylinders are arranged in V-form. 110

In the atomizers hereinbefore referred to using a piston or a diaphragm in connection with the needle valve, the extent of opening of the needle valve is variable automatically in accordance with variations of pressure 115 within the vaporizer, such variations in pressure within the vaporizer resulting from throttling the fresh air entering the crank case through manipulation of the air throttle valve 45 or the throttle valve of a carburetor should such be fitted to the air intake of the crank case. It may be desirable, however, in some instances to throttle the engine by manually adjusting the needle valve which controls the supply of fuel oil 120 to the vaporizer. Such an arrangement is shown in Figures 8 and 9 wherein the atomizer 109 which is in the form of a plug fitted into the top of the venturi has a bore 110 for the fuel oil, the bottom of this bore be- 130

ing formed with a valve seat 111, and a needle valve 112 is fitted into the bore and arranged to cooperate with the seat 111 to control the amount of fuel oil supplied to the venturi through the aperture 113. The needle valve stem has a portion 114 which is threaded in the upper portion of the atomizer plug and a crank 115 fixed to the upper end of the needle valve stem is adapted to be connected to suitable manual control means. A vaporizer disk or plate 116 is attached to the lower end of the vaporizer plug opposite to the aperture 113, and said plate is adapted to receive thereon the fuel oil introduced through the aperture 113. This plate 116 may be formed as a part of the plug, as is the case in Figures 8 and 9, or it may be constructed as a separate plate 116^a, as shown in Figure 10, the plate being fixed to the plug opposite to the aperture 113 by suitable pins 117. This plate 116^a may either be convexed, as shown in Figure 11, it may be concaved, as shown in Figure 12, or it may be flat, as shown in Figure 13. In using a manually controlled needle valve for the fuel, as shown in Figures 8 and 9, it is desirable to feed the fuel thereto under a substantially constant pressure. A system for accomplishing this result is shown in Figure 16, the fuel being contained in a suitable tank 118 and being conducted from the tank through a pipe 119 which leads to the inlet 120 of the vaporizing plug, and appropriate means is provided for maintaining an approximately constant air pressure above the fuel in the tank. As shown, a hand or power pump 121 may be connected to the top of the tank by a pipe 122 which is provided with suitable check-valves 123 and, also, the pressure of the air in one of the compartments of the crank case of the engine may be utilized to maintain appropriate pressure on the fuel in the tank 118, a pipe 124 being shown as leading from the fitting 125 in one of the crank case compartments to the top of the tank 118, and appropriate check-valves 126 are provided in the pipe 124.

By using vaporizers, such as shown in Figures 8 and 9, the necessity of extending the fuel float chamber beneath the venturi is avoided and the depressed apex of the venturi in which the heavier fractions of the fuel oil accumulate may be heated more directly and to a higher temperature, as indicated by the construction shown in Figure 9. In this instance, the pipe 65 which conducts the exhaust gases to the heating jacket of the vaporizer leads to a wall 127 which forms the bottom of the center or lowest portion of the venturi, thus forming a hot spot. This arrangement enables the heavier fractions of the fuel oil accumulated in the depression of the venturi to be heated more directly and to a higher temperature,

thus insuring complete vaporization thereof. The circulation of the exhaust gases through the heating jacket of the vaporizer is otherwise the same as described in connection with the construction shown in Figures 1-5 inclusive.

The mode of operation of the engine may be described, briefly, as follows: Rotation of the crank shaft causes the pistons and barrels of the pair of cylinders to reciprocate in opposite or reverse directions. During the upward stroke of either piston, the mixture above the piston and contained in the combustion chamber of the respective cylinder is compressed therein, this compressed charge being ignited by the spark plug at the usual time and in the usual way. During this upward stroke of the piston, its valve 37 is closed, thus preventing down-flow of fluid from the respective barrel to the crank case. When the piston approaches the limit of its upward stroke, its lower end uncovers the air intake ports 23, the partial vacuum formed in the respective crank case compartment by the upward stroke of this piston causing a charge of air to enter this crank case compartment through the ports 23. This upward movement of the piston causes the fluid above it to be displaced, inducing a flow of fluid through the venturi toward the opposite cylinder of the pair. While one piston is moving upwardly and performing the functions described, the other piston of the pair is concurrently moving downwardly. During the first part of the downward movement of such piston, the valve 37 therein is closed owing to equilibrium of pressure in the vaporizer and the crank case compartment pertaining to the descending piston, the air contained in such crank case compartment being compressed during the down stroke of such piston. As the descending piston approaches the limit of its down stroke, the pressure of the air in the corresponding crank case is further compressed to the point where it overbalances the pressure in the vaporizer, causing the valve 37 of the descending piston to open, allowing the compressed air from the crank case to flow upwardly within the corresponding piston barrel 30. Further approach of the descending piston to the limit of its down stroke causes the upper end of such piston to uncover and open the exhaust ports 22 and to simultaneously bring the ports 41 in its respective piston barrel into communication with the combustion chamber of the corresponding cylinder whereupon part of the air from the respective crank case compartment will flow outwardly through the ports 41 in the piston barrel, driving ahead of it the exhaust gases from the preceding explosion, following which the mixture from the vaporizer will enter the upper open

end of the respective piston barrel and flow into the combustion chamber of the cylinder through the ports 41, the explosive mixture forming a stratum above the air stratum 5 and occupying a position to insure the most certain and efficient ignition. Figure 15 shows diagrammatically the contents of one of the cylinders at this moment, *a* representing the stratum of fresh explosive mixture, *b* the stratum of fresh air, and *c* the stratum of any residual exhaust gases that may remain in the cylinder, although the burned gases will ordinarily be expelled completely from the cylinder owing to the excess capacity 15 of the crank case, as is the case in my former Patent, No. 1,178,648, granted April 11, 1916, upon which the present invention is an improvement. In this diagram (Figure 15), the piston barrel is shown provided with circumferential corrugations 49 which may be used to strengthen the piston barrel and prevent warping thereof. The cycle of operations described alternates in the two cylinders of the pair 20 and the speed and power of the engine may be controlled in cases where the fuel-regulating needle valve is provided with a piston or diaphragm by throttling the volume of air entering the crank case compartments 25 of the engine, it being obvious that a diminution in the volume of air entering the crank case will result in a diminution in the volume of air entering the vaporizer, in consequence of which the pressure developed 30 within the vaporizer by the pumping actions of the pistons will be correspondingly diminished, this diminished pressure causing the needle valve to open to a less extent than is the case where greater volumes of air are admitted to the crank case compartments. In the construction employing a manually adjustable needle valve, the crank case compression and the compression within the vaporizer are constant and 35 the speed and power of the engine are controlled by adjusting the needle valve manually to vary the amount of fuel admitted by the vaporizer plug.

During the operation of the engine, the cylinders are cooled exteriorly by the fins which dissipate the heat to the air, or, the cylinders may be cooled exteriorly by water jackets when such is desirable, and the engine is cooled interiorly by the incoming fresh air flowing upwardly through the pistons and the piston barrels thereon, the piston barrels being composed of relatively thin metal capable of conducting the heat rapidly from the combustion chamber of the cylinder and adjacent parts to the air flowing upwardly through the barrel. The heat thus conducted from the combustion chamber and adjacent parts of the cylinder and piston is taken up by the incoming fresh air and 60 the latter is thereby heated to a temperature 65

that will enable it to combine most efficiently with the fuel oil to form a superheated dry gaseous mixture. At the same time the fuel oil is heated to a relatively high degree within the vaporizer by the heat absorbed from the exhaust gases, the heavier fractions of the fuel oil being especially heated to a relatively high temperature. Furthermore, the explosive mixture is made within the vaporizer not only at relatively high temperature 70 but also under a pressure above atmospheric pressure, the pumping action of the pistons maintaining a pressure above atmospheric pressure within the vaporizer. This pressure maintained within the vaporizer preferably averages several pounds above atmospheric pressure.

During operation of the engine on fuel oil, any heavy fractions of such oil that may tend to accumulate in the low portion of the 85 venturi, due to the relatively high temperature conditions, will be subjected to the to-and-fro scrubbing or washing action of fresh fuel oil, induced by the reversely reciprocating motions of the pistons, with the result 90 that the heavy fractions are dissolved by the lighter fractions of the fresh fuel and in consequence they become picked up and carried by the mixture. The remainder of the vaporizer is heated uniformly, or substantially so, and hence vaporization of the fuel oil and conversion thereof into a superheated dry gaseous mixture is uniform. The upturned lips at the ends of the venturi enable this to-and-fro washing action of the fuel oil 100 to take place without spilling over into the cylinders. If, however, the fuel oil should pass these lips, it will be shot upwardly against the highly heated walls of large area 105 at the ends of the vaporizer chamber and hence very little if any raw or unvaporized fuel will reach the cylinders. The vaporizer offers no obstruction to the flow of the mixture on its way to the cylinders, nor does the mixture have an opportunity to condense, as is the case with most intake manifolds, and, furthermore, each cylinder receives the same amount of the fuel mixture and hence uniformity in the power impulses of the cylinders is attained. Owing to the 115 high temperature of a superheated dry gaseous mixture, which ranges between 400° and 600° F., according to the quality of the fuel employed preignition in the working cylinders and loss of power, due to low 120 volumetric efficiency, would be liable to occur in internal combustion engines of the usual construction. Such difficulties, however, are avoided by the present invention, the fresh air which scavenges the cylinder acting first 125 to cool the piston and cylinder and later, meeting the hot mixture, causing part of the mixture to be condensed, producing a smoke-like fog which gives up its latent heat to the air while entering the working cylinder, 130

thereby avoiding preignition, the condensed mixture being re-vaporized upon striking the upper wall of the combustion chamber. Also, the internal air cooling of the working cylinder enables higher compression pressures to be employed without preignition, it avoids any great loss of power as it prevents undue initial volumetric expansion of the mixture before entering the cylinder, 10 and it also enables the engine to operate on the two-cycle principle with externally air-cooled cylinders and high speeds, and large power outputs may be attained without undue heating and wear of the working 15 mechanism.

Another feature of the invention which effects greater efficiency and economy in the running of the engine concerns the mode in which the fuel mixture is introduced into 20 the cylinder. According to the present invention, fresh air from the crank case enters the cylinder after the exhaust ports have opened, such air following the exhaust gases on their way to the exhaust ports, thus 25 scavenging the cylinder and especially the upper portion of burned gases, this scavenging air as it flows upwardly in the respective piston barrel meeting the fuel mixture as the latter comes over from the opposite 30 ascending piston and thus holding the fuel mixture back in the upper portion of the barrel until the pressure in the vaporizer becomes so reduced that the mixture flows automatically into the upper end of the combustion 35 chamber which has been scavenged by the previously entering fresh air. In this way, a pure, undiluted fuel mixture occupies the upper end of the combustion chamber in the zone of the spark plug and 40 ignition of the charge and propagation of the flame are effected with greater certainty and efficiency, with the result that the power derived from the explosion is increased. Also, the fuel mixture, fresh scavenging air, 45 and any burned gases remaining in the cylinder lie in separate strata, and hence diluting or adulterating of the fuel mixture, to which kerosene or fuel oils are more sensitive than gasoline, is avoided.

50 The present invention enables kerosene and other fuel oil to be used efficiently as a fuel for internal combustion engines adapted for general purposes, and it provides an efficiently operative air-cooled two-cycle engine which is of relatively light weight 55 which particularly adapts it for use in aeroplanes and automobiles, the mode described for attaching the barrels to the pistons and for fitting the valves in the piston heads 60 enabling the use of aluminum pistons which are light in weight and hence they materially reduce vibration, especially when operating at high speed, while the mode of interchanging heat between the incoming fresh 65 air and the internal parts of the engine

insures efficient preparation of the fuel oil for combustion and avoids overheating at high speed or under a heavy load.

I claim as my invention:

1. In an internal combustion engine, the 70 combination of a fuel mixture vaporizer having a well to contain unvaporized fuel and means for conducting exhaust gases from the engine to and from the same for heating it, and means regulated in accordance with the temperature of the exhaust gases leaving the vaporizer for controlling the flow of exhaust gases to the well of the vaporizer. 75

2. In an internal combustion engine, the 80 combination of a fuel storage chamber of substantially constant displacement having a heating jacket for heating constituents of fuel charges therein, such jacket being provided with an inlet and an outlet for exhaust gases from the engine, and means regulated by the temperature of the exhaust gases at said outlet for controlling the flow of the exhaust gases to said outlet. 85

3. In an internal combustion engine, the 90 combination of a fuel vaporizer having a depression therein for the collection of unvaporized portions of the fuel, and a heating jacket provided with an exhaust gas inlet leading directly to said depression and 95 an outlet for the discharge of the exhaust gases from the jacket, means for controlling the flow of exhaust gases to said inlet, and a thermostat controlled directly by the temperature of the exhaust gases at said outlet 100 and operatively connected to said controlling means. 105

4. In an internal combustion engine, the combination of a fuel vaporizer provided with a heating jacket having an inlet and 110 a plurality of outlets located substantially equidistantly from said inlet, means for controlling the flow of a heating medium to said inlet, and a thermostat subject to the temperature of the heating medium at said outlets for regulating said controlling means. 115

5. In an internal combustion engine, the combination of a fuel vaporizer having a heating jacket provided with an inlet and an outlet, an exhaust gas supply conduit 115 connected to said inlet and having an escape valve, an exhaust gas discharge conduit connected to said outlet and provided with an escape valve, and means connecting said valves to cause synchronous movements 120 thereof in reverse directions. 125

6. In an internal combustion engine, the combination of a fuel vaporizer provided with a heating jacket having an inlet and an outlet, an exhaust pipe leading from the 125 engine and connected to said inlet, an exhaust discharge pipe leading from said outlet, escape valves in both pipes connected to move one valve toward open position while the other valve moves toward closed posi- 130

tion, and means responsive to variations in the temperature of the exhaust gases at said outlet for controlling said valves.

7. In an internal combustion engine, the combination of a fuel vaporizer provided with a heating jacket having an inlet and an outlet, an exhaust pipe leading from the engine and connected to said inlet and to a direct discharge pipe, an exhaust discharge pipe leading from said outlet, exhaust gas escape valves for both of said discharge pipes having means connecting them to cause reverse movements thereof and a thermostat subject to the temperature of the exhaust gases at said outlet and operatively connected to said valves to control them.

8. In an internal combustion engine, the combination of a fuel vaporizer provided with a heating jacket having an inlet and an outlet, means for supplying exhaust gases to said inlet, an exhaust discharge conduit leading from said outlet, valve means for controlling the supply of exhaust gases to said jacket, and a thermostat located within said discharge conduit and operative to actuate and control said valve means in accordance with temperature variations of the gases discharging from the jacket.

9. In an internal combustion engine, the combination of a fuel vaporizer containing a depressed portion adapted to trap unvaporized fuel, and fuel mixture outlets extending in opposite directions therefrom and means for conducting exhaust gases initially to the wall forming said depressed portion and subsequently to the walls of said outlets.

10. In an internal combustion engine, a fuel vaporizer containing a venturi formed with an intermediate depressed portion and provided with a heating jacket, said jacket having an inlet for a heating medium located adjacent to said depressed portion, and outlets for such medium located toward the opposite ends of the venturi.

11. In an internal combustion engine, a fuel vaporizer containing a venturi having an intermediate depressed portion and chambers at the ends of the venturi to communicate with the cylinders, the vaporizer being provided with a heating jacket the inlet of which is located adjacent to said depressed portion and the outlets of which are located adjacent to said chambers at the ends of the venturi.

12. In an internal combustion engine, the combination of a fuel mixture vaporizer having a well forming a trap for the collection of unvaporized fuel and means for conducting exhaust gases from the engine initially to said well and then to other portions of the vaporizer for heating the same, and an exhaust-heat-regulator governed by the temperature of the exhaust gases after they have acted on the vaporizer for controlling

the heat supplied to the vaporizer by the exhaust gases.

13. In an internal combustion engine, the combination of a fuel vaporizer having a portion to receive unvaporized fuel, and a heating jacket provided with an inlet leading directly to said portion, and an outlet for the passage therethrough of exhaust gases from the engine, means for controlling the flow of such gases to said jacket, and a thermostat subject to the temperature influence of the exhaust gases at the outlet of said jacket and operatively connected to said controlling means.

14. In an internal combustion engine, the combination with a fuel vaporizer having a well to trap unvaporized fuel and means for applying exhaust gases from the engine directly to said well for heating it, and a thermostat arranged to be subjected to the direct temperature influence of the exhaust gases after they have acted on the vaporizer for controlling the amount of heat supplied by such gases to the vaporizer.

15. In an internal combustion engine, a fuel vaporizer containing a venturi formed with a depressed portion adapted to trap unvaporized fuel, the wall forming said depressed portion having corrugations, means for inducing a flow of fluid in reverse directions through said venturi and means for conducting exhaust gases to such corrugated wall.

16. In an internal combustion engine, a fuel vaporizer containing a depressed portion adapted to contain unvaporized fuel and outlet passages for vaporized fuel extending in opposite directions from said depressed portion, the vaporizer being provided with a heating jacket, said jacket having an inlet for a heating medium located adjacent to said depressed portion and branched passages for the fuel outlet passages, the wall of said depressed portion having corrugations adjacent to said inlet and in a position to be subjected to the influence of said heating medium.

17. In an internal combustion engine, the combination of a fuel vaporizer containing a depressed portion adapted to trap unvaporized fuel and outlets for vaporized fuel communicating with said depressed portion at opposite sides thereof, the lower wall of said depressed portion being corrugated exteriorly, and means for conducting heating fluid to said corrugated wall.

18. In an internal combustion engine, the combination of a vaporizer having an intermediately depressed venturi adapted to receive atomized fuel oil, and means for inducing a to-and-fro flow of fluid in said venturi to produce a gaseous mixture of fuel oil and air, the ends of the venturi being adapted to communicate with cooperating cylinders of the engine and the ends of the

venturi having upwardly projecting lips to impede or prevent spilling of unvaporized fuel oil into the cylinders.

19. In an internal combustion engine, the combination of a vaporizer having a heating jacket and containing a venturi the ends of which are adapted to communicate with co-operative cylinders of the engine and the intermediate apex of which is depressed, 5 means for supplying to and atomizing fuel oil within said venturi, pistons reciprocable in reverse directions in the cylinders and operative to supply air to the vaporizer and to induce a to-and-fro movement of fluid there-

in, and upstanding lips on the lower walls 15 of the venturi toward the opposite ends thereof adapted to retard the passage of unvaporized fuel oil to the cylinders and to deflect such unvaporized fuel oil against heated walls of the vaporizer. 20

In testimony whereof I have hereunto set my hand in presence of two subscribing witnesses.
